US0D1033828S

(12) United States Design Patent (10) Patent No.: US D1,033,828 S
(45) Date of Patent: * Jul. 9, 2024

(54) SHOE

(71) Applicant: NIKE, Inc., Beaverton, OR (US)

(72) Inventor: Erick Ikeda, Beaverton, OR (US)

(73) Assignee: NIKE, Inc., Beaverton, OR (US)

() Term: 15 Years

(21) Appl. No.: 29/843,459

(22) Filed: Jun. 21, 2022

(51) LOC (14) Cl. 02-04

(52) U.S. Cl.

USPC D2/947; D2/972

(58) Field of Classification Search

USPC D2/896, 900, 902, 906-912, 916-924,

CLAIM

The ornamental design for a shoe, as shown and described.

DESCRIPTION

FIG. 1 is a front perspective view of a shoe showing my new design;

FIG. 2 is a side view thereof;

FIG. 3 is a rear perspective view thereof;

FIG. 4 is a rear view thereof;

FIG. 5 is an opposite side rear perspective view thereof;

FIG. 6 is an opposite side view thereof; and,

FIG. 7 is an opposite side front perspective view thereof. The two racetrack shaped broken lines within the shaded area form no part of the claimed design. The broken lines depicting the remainder of the shoe form no part of the claimed design.

1 Claim, 7 Drawing Sheets
